CONVEYER CONTROL APPARATUS

Lester O. Reichelt, Cranford, and Gordon C. Spillman, Roselle, N. J., assignors to Western Electric Company, Incorporated, New York, N. Y., a corporation of New York

Application November 10, 1942, Serial No. 465,120

12 Claims. (Cl. 193—40)

This invention relates to article conveyer control apparatus and more particularly to an apparatus for controlling the movement of reels rolling on an inclined trackway.

It is an object of the present invention to provide a simple apparatus for accurately regulating the travel of articles on a conveyer.

In accordance with one embodiment of the invention, an apparatus is provided for regulating the speed of travel of reels rolling along a trackway wherein a reel entering a predetermined blocked section of the trackway initiates the operation of an electric circuit, which circuit automatically effects the release of a blocking device in said section of the trackway after a predetermined interval of time has elapsed to permit the reel which tripped the circuit to resume its travel along the trackway. As the reel passes out of engagement with the blocking device, it actuates a circuit restoring switch, which restores the circuit to normal position for operation by a succeeding reel.

A better understanding of the invention will be had by reference to the following detailed description when considered in conjunction with the accompanying drawings, wherein

Fig. 1 is a side elevational view of a conveyer, for use in connection with a flyer strander and provided with control apparatus constructed in accordance with the present invention, parts of the apparatus being broken away to illustrate the construction of parts positioned in the rear thereof;

Fig. 2 is a transverse vertical sectional view taken substantially along the line 2—2 of Fig. 1 in the direction of the arrows;

Fig. 3 is a circuit schematic showing, diagrammatically, the electrical connections for controlling the mechanical structure illustrated in Figs. 1 and 2;

Fig. 4 is an enlarged fragmentary plan section through the control portion of the apparatus taken substantially along the line 4—4 of Fig. 1 in the direction of the arrows;

Fig. 5 is a longitudinal vertical sectional view taken substantially along the line 5—5 of Fig. 4 in the direction of the arrows; and

Fig. 6 is a transverse vertical sectional view taken substantially along the line 6—6 of Fig. 5 in the direction of the arrows.

In the drawings, wherein like reference characters designate the same parts throughout the several views, a reel 10 is shown in dot and dash lines in a number of positions in the apparatus. The apparatus comprising the herein disclosed

embodiment of the present invention is adapted for use in connection with the mechanism disclosed in the co-pending application of Axel C. Nystrom and Lester O. Reichelt, Serial No. 397,402, filed June 10, 1941, wherein the reels 10 roll down a conveyer track 11, the left end (Fig. 1), of which is rounded, as shown at 12, to permit reels 10 to roll off the conveyer track 11 onto a trackway 13. As seen most clearly in Fig. 2, the trackways 11 and 13 are comprised of angle members 14 and 15 and 16 and 17, respectively. The angle members 14 and 15 are mounted upon suitable supporting brackets 18 and 19, respectively, which extend from the upper surface of angle iron frame members 20 and 21. The angle members 14 and 15 are rounded, as indicated at 12, and the angle members 16 and 17 are curved on an arc having the same center point as the rounded portion 12 of the angle members 14 and 15. The angle members 16 and 17 extend upwardly to provide a guide 22, forming an extension of the trackway 13 and serving to direct reels 10 rolling off the left end of the track 11 onto the trackway 13. The angle members 20 and 21 and the angle members 16 and 17 are supported by posts 23—23 and 24—24, which are fixed in base angle members 25 and 26.

It will be noted, by reference to Fig. 1, that the trackway 13 slopes downwardly to the right and that the track 11 slopes downwardly to the left. Thus, the reels 10 on the track 11 will roll down the track 11 and off the end of it and thence onto the lower track 13. Due to the fact that the weight of the reels varies to a considerable extent, their momentum will vary to an appreciable extent and reels on the trackway 13 might be damaged unless they are checked after they have dropped off the trackway 11.

In the present embodiment of the invention, this is accomplished by forcing each reel to engage a pair of wedge plates 30 and 31 in direct vertical alignment with the angle members 16 and 17. The wedge plates 30 and 31 are supported by the frame members 20 and 21, being mounted on the underside of supporting plates 32 and 33 and an angle support plate 34, which plates are, in turn, mounted on the horizontal flange of the frame members 20 and 21. A reel 10, which has dropped off the track 11 and rolled down the steeply sloping portions of the angle members 16 and 17 will be wedged against the wedge plate 30 by an inclined platform 35, which is normally positioned, as shown in Figs. 1 and 5. The platform 35 is held in place on the angle members 16 and 17 by pins 36 and 37, which extend through

apertures 38 and 39 in the angle members 16 and 17 and are fixed to the under side of the platform 35. The pins 36 and 37 are each provided with a washer 40, which is locked onto its pin by a cotter pin 41, whereby the platform 35 is permitted to move relatively to the angle members 16 and 17 to a limited extent. Adjacent its right end, the platform 35 has pivoted on its under side a pair of plungers 42 and 43, which extend down through a pair of cylinders 44 and 45, respectively. The lower ends of the plungers 42 and 43 are threaded to receive lock nut assemblies 46 and 47, which serve to prevent the plunger and, consequently, the platform 35, from moving upwardly beyond the position shown in Fig. 5. Encircling the plungers 42 and 43 are a pair of compression springs 48 and 49, respectively, which engage the bases of the cylinders 44 and 45 and the under side of the platform 35 normally to urge the platform to the position shown in the various views.

Mounted on the angle members 16 and 17 are a pair of tapered members 55 and 56, which are designed to guide a reel 10 onto the platform 35. The tapered member 56 is pivotally mounted on a pin 57 and is normally urged upwardly (Fig. 5) by a plunger 58 of a switch 59. The switch 59 is normally open and is adapted to be closed, upon depression of the tapered member 56, to depress the plunger 58 and thereby close the switch. The switch 59 (Fig. 3) is connected to a lead 60 running to one side of a current source 61. The other side of the switch 59 is connected through a normally closed switch 62 so that when the switch 59 is closed, the lead 60 will be connected through the switches 59 and 62 to windings 63 and 64 of a double wound relay 65. The other end of the windings 63 and 64 is connected through a lead 66 to the opposite side of the current source 61. The winding 63 of the relay 65 controls the operation of normally open contact 67 and immediately upon the closure of the switch 59, the winding 63 will be energized to close contacts 67 for providing a holding circuit from lead 60 through switch 62 to the windings 63 and 64.

The winding 64 of the relay 65 is provided with a suitable means for delaying its operation, for example, a copper slug 68. Therefore, the winding 64 will not be effective to close its associated contacts 69 immediately upon the closure of the switch 59, but will delay closing the contact 69 for a predetermined interval. Closure of the contacts 69 will connect the lead 66 to one side of the winding 70 of a solenoid 71, the other side of the winding of which is connected directly to the lead 60. The solenoid 71 is provided with a plunger 72 adapted to be attracted upon energization of the solenoid and when the switch 59 closes, a circuit will be completed to the winding 63 of relay 65 to close contacts 67 and current will also be supplied through the switch 62 to the winding 64. This circuit, to hold the relay 65 energized, will be maintained until the switch 62 is opened and the continued application of current to the winding 64 will, after a predetermined interval, cause the closure of switch 69, thereby to energize the solenoid 71.

The solenoid 71 is mounted upon a suitable bracket 80 and its plunger 72 is connected to a slideable table 81, which is mounted for sliding movement to the right or left (Figs. 4 and 5) on a pair of rollers 82, mounted in a suitable housing 83. The sides of the housing 83 have retaining plates 85 fixed thereto for retaining

the table 81 in position on the rollers 82. Extending upwardly from the table 81 is a bracket 86, to which is attached the left end of a contractile spring 87 (Figs. 4 and 5). The right end of the contractile spring 87 is adjustably attached to a bracket 88 mounted on the end of the housing 83 by means of an adjustment screw 89.

From the foregoing, it is believed to be apparent that the table 81 is normally urged to the right (Figs. 4 and 5) into engagement with the end wall of the housing 83 and, upon energization of the solenoid 71, the table 81 will be moved to the left. The table 81 has extending upwardly from it a pair of projections 90 to which there are pivoted toggle links 91 (Figs. 4, 5 and 6). The toggle links 91 are, in turn, pivoted at their upper ends to projections 92 extending downwardly from the under side of the platform 35. By reference to Fig. 5, it will be seen that the toggle links 91 receive pivot pins 93, which pivotally connect them to the projections 92, in elongated slots 94 so that the platform 35 is not held rigidly in its upper position by the toggle 91, but is permitted a limited amount of movement with respect to the link 91. Thus, when a reel 10 rolls onto the platform 35, it will depress the platform slightly against the action of the springs 48 and 49 and the rims of the reel will not be damaged. The switch 62 is adapted to be actuated by a reel after the reel has been released from the platform 35 and, accordingly, the switch 62 is mounted on the under side of the angle member 17 and is adapted to have its plunger 100 actuated by a lever 101 mounted for oscillation on a pin 102, which is, in turn, mounted in a block 103.

A better understanding of the invention will be had by reference to the following brief description of the mode of operation thereof. After the reels have been used in some previous operation, for example, those operations described in detail in the co-pending application of Axel C. Nystrom and Lester O. Reichelt, Serial No. 397,402, filed June 10, 1941, the reels may be permitted to roll down the sloping conveyer track 11 and from the track 11 onto the trackway 13. As the reels leave the steeply sloping section of the trackway 13 and approach the gradually sloping section thereof, they will engage the tapered member 56 and depress the plunger 58 to close switch 59. The closure of switch 59 will supply current to the windings 63 and 64 of the relay 65 through normally closed switch 62. As soon as the reel 10 rolls off the tapered member 56, the switch 59 will open, but the circuit to the windings 63 and 64 will be maintained through contacts 67, which closed as soon as the winding 63 was energized. Thus, the circuit to the windings 63 and 64 will be maintained through normally closed switch 62 until the switch 62 is opened by the reel 10 engaging the lever 101, which opens switch 62. The winding 64 of relay 65 will be energized as soon as the switch 59 is closed and will be maintained energized as long as the switch 62 is closed and the switch 62 will remain closed until the reel 10 effects its opening. After the circuit to the winding 64 of relay 65 has been maintained for a predetermined interval, the slow-to-close contacts 69 will close and will complete the operating circuit to the solenoid 71. When the solenoid 71 is energized over this circuit, the table 81 will be drawn to the left (Figs. 4 and 5) and will permit the weight of the reel 10 wedged between the platform 35 and the wedge plate 30 to depress

the forward end of the platform 35 around the plungers 42 and 43. The springs serve to take up the shock of the reel entering the section in which it is to be wedged against the wedge plate 30. Furthermore, since the table 81 is held in the framework 83 by the retaining plates 85, it will pull the platform 35 downwardly and the reel 10 will thus, upon energization of the solenoid 71, roll onto the gradually inclined section of the trackway 13. As the reel 10 rolls off the platform 35, it will engage the lever 101 to cause the lever 101 to open switch 62. When switch 62 opens, the circuit from lead 60 through closed contact 67 and switch 62 to the windings of relay 65 will be broken and the circuit will be restored to normal position, as shown in Fig. 3, ready to start another cycle of operation.

What is claimed is:

1. An apparatus for regulating the movement of articles on a conveyer, means on the conveyer for blocking movement of an article, means on the conveyer positioned between the entrance end of the conveyer and said blocking means for initiating a releasing operation of said blocking means, means controlled by said means on the conveyer between the entrance end of the conveyer and the blocking means for moving said blocking means out of the path of the article after a predetermined interval, and means on the conveyer between the blocking means and the exit end of the conveyer for resetting the means for releasing the blocking means under control of an article released by the blocking means.

2. In a conveyer for reels, the trackway down which reels may roll, wedging members along said trackway, one of which is movable, means operated by an article for initiating a cycle of movement of the movable wedging member, a time delay mechanism controlled by said means operated by the article for moving said movable wedging member a predetermined time after the operation of the means operated by the article, and means also operated by the article for resetting said last mentioned means.

3. In an apparatus for regulating the travel of reels along an inclined track comprising a wedge plate above said track, a platform on said track for receiving reels thereon, a slideable plate positioned beneath said trackway, toggle mechanism interconnecting said platform and slideable table, a solenoid for moving said table to effect movement of the platform through the toggle mechanism, means operable by the reel for preparing the solenoid for operation, and automatic means under control of said last mentioned means for supplying current to energize the solenoid a predetermined time after said last mentioned means is operated.

4. In an inclined trackway for reels, an inclined platform for receiving reels, a wedge plate cooperating with said platform to wedge a reel between them, a toggle mechanism for holding said platform in position with a reel between it and the wedge plate, a solenoid operable for releasing said platform, and a time delay mechanism operable under control of a reel on the trackway for initiating operation of the solenoid a predetermined interval after the article engages the platform.

5. In an inclined trackway for reels, an inclined platform for receiving reels, a wedge plate cooperating with said platform to wedge a reel between them, a toggle mechanism for holding said platform in position with a reel between it and the wedge plate, a solenoid operable for re-

leasing said platform, a time delay mechanism operable under control of a reel on the trackway for initiating operation of the solenoid a predetermined interval after the article engages the platform, and means operable by the article after it is released from the platform for releasing the solenoid.

6. An apparatus for regulating the movement of articles on a conveyer comprising an upwardly inclined pivoted track, a fixed horizontal member cooperating with said track to wedge an article between them and stop its movement on the conveyer, a switch operable by an article just prior to the article's engagement with the inclined track, and means controlled by said switch for moving the track out of position to cooperate with the horizontal member after the lapse of a predetermined time interval.

7. In an apparatus for controlling the travel of articles on a conveyer, means movable to stop an article on the conveyer, and a circuit controlled by the article including a switch closed by the article, a solenoid operable to move the means for stopping the article on the conveyer to position to release the article, and time delay means operable under control of the switch for initiating operation of the solenoid a predetermined time after the article operates the switch.

8. In an apparatus for controlling the travel of an article on a conveyer, means normally blocking movement of an article on the conveyer, means for moving the blocking means out of its normal position, a control circuit for said moving means including means operable by an article for initiating operation of the circuit, means controlled by the last mentioned means for supplying power to operate the moving means after a predetermined time interval, and means controlled by the article for resetting the circuit.

9. In an apparatus for controlling the travel of articles on a conveyer, means movable to stop an article on the conveyer, and a circuit controlled by the article including a switch closed by the article, a solenoid operable to move the means for stopping the article on the conveyer to position to release the article, and a time delay relay operable under control of the switch for initiating operation of the solenoid a predetermined time after the article operates the switch.

10. In an apparatus for controlling the travel of articles on a conveyer, means movable to stop an article on the conveyer, a circuit controlled by the article including a switch closed by the article, a solenoid operable to move the means for stopping the article on the conveyer to position to release the article, a time delay relay operable under control of the switch for initiating operation of the solenoid a predetermined time after the article operates the switch, and a locking circuit operable under control of said switch for maintaining the circuit to the time delay relay.

11. In an apparatus for controlling the travel of articles on a conveyer, means movable to stop an article on the conveyer, a circuit controlled by the article including a switch closed by the article, a solenoid operable to move the means for stopping the article on the conveyer to position to release the article, a time delay relay operable under control of the switch for initiating operation of the solenoid a predetermined time after the article operates the switch, a locking circuit operable under control of said switch for maintaining the circuit to the time delay relay, and a second means controlled by the article for releasing the locking circuit.

12. In an apparatus for controlling the travel of articles on a conveyer, means movable to stop an article on the conveyer, a circuit controlled by the article including a switch closed by the article, a solenoid operable to move the means for stopping the article on the conveyer to position to release the article, a time delay relay operable under control of the switch for initiating opera-

tion of the solenoid a predetermined time after the article operates the switch, a locking circuit operable under control of said switch for maintaining the circuit to the time delay relay, and a switch operable by the article after the article is released for opening the locking circuit.
